UNITED STATES PATENT OFFICE.

FRANCIS H. RICHARDS, OF HARTFORD, CONNECTICUT, ASSIGNOR TO ECKLEY B. COXE, OF DRIFTON, PENNSYLVANIA.

TRAVELING-GRAVE FURNACE.

SPECIFICATION forming part of Letters Patent No. 527,449, dated October 16, 1894.

Application filed February 20, 1894. Serial No. 500,887. (No model.)

To all whom it may concern:

Be it known that I, FRANCIS H. RICHARDS, a citizen of the United States, residing at Hartford, in the county of Hartford and State of Connecticut, have invented certain new and useful Improvements in Traveling-Grate Furnaces, of which the following is a specification.

This invention relates to traveling-grate furnaces; the object of the invention being to provide an improved non-rotary traveling grate, comprising a series of independently movable sections, adapted for carrying a layer of fuel continuously along in the furnace, after the manner of the endless traveling grate, or chain-grate, heretofore used for that purpose; also to provide means for imparting a relatively slow forward movement to the several sections constituting the grate, and to impart a quick return movement to said sections successively, whereby the majority of the grate-sections have a slow forward movement during the quick return movement of one or more of the other sections, thus maintaining a continuous or uninterrupted feed of the fuel, irrespective of the shifting movements of the grate-sections.

In the drawings accompanying and forming a part of this specification, Figure 1 is a sectional side elevation of a furnace embodying my present improvements. Fig. 2 is a plan view of the same, partially in horizontal cross-section, parts of the grate-mechanism being broken away to more clearly illustrate the construction thereof. Fig. 3 is a transverse sectional elevation, taken on dotted line *a—a*, Fig. 1, showing the parts at the left of said line. Figs. 4, 5 and 6 are detail views, in side elevation, of a portion of one of the grate-sections and the mechanism for imparting the requisite traveling movement to said section, said figures showing three successive positions of the grate-section and its operating mechanism. Fig. 7 is a vertical cross-section of the furnace, showing the grate-bars and the floor-plates carried thereby. Fig. 8 is a sectional plan view of a portion of the furnace showing the grate-bar actuating mechanism, the grate-bars being removed.

Similar characters designate like parts in all the figures.

For the purpose of illustrating the application and operation of the elements and combinations comprised in my present invention, I have shown the same in connection with a furnace of the class described in Letters Patent of the United States, No. 499,716, granted to Eckley B. Coxe June 20, 1893, to which reference may be had for a more complete description of some of the details herein shown and only briefly described.

The furnace illustrated in the drawings has the usual inclosing-walls at the sides and ends thereof, and is shown provided with the ordinary furnace-roof. The side-walls are designated in a general way by 3 and 4, respectively, the roof by 2, the usual bridge-wall by 5, and the front and back walls by 6 and 6', respectively. At the forward end of the furnace, this is provided with a fuel supply hopper, H, from which fuel is supplied to the furnace-chamber through the inclined chute or opening 7, in a well-known manner.

The furnace is shown provided with a traveling grate, designated in a general way by G, and which, in this instance of my invention, comprises a series of independent longitudinal grate-sections, herein shown as six in number and designated by D, D', E, E', and F, F', respectively. These grate-sections are adapted to have longitudinal reciprocatory movements imparted to them, as will be hereinafter described.

Underneath the grate G is placed an air-blast apparatus, which, in the preferred form thereof herein shown, comprises the successive air-blast chambers *a*, *b* and *c*, constructed and arranged in accordance with the invention described and claimed in the aforesaid Letters Patent No. 499,716. Said air-blast apparatus is supported by some suitable connection with the side-walls 3 and 4 of the furnace; and the upper edges of the division-walls 8, 8', 8'' and 8''' of said air-blast apparatus are shown provided with guides, M, for holding in place and guiding the bars or sections of the grate G.

In practice, suitable grate-section-support-

ing rollers, as 9 and 10, may be provided at one or more points in the length of the grate-sections for reducing the friction of said sections as they are moved longitudinally of the furnace.

The air-blast chambers *a*, *b* and *c* are shown provided with air-supply pipes *a'*, *b'* and *c'*, in which may be placed the regulators or valves *a''*, *b''* and *c''* (shown by dotted lines in Fig. 1) for independently regulating the pressure of the air-blast in the successive air-blast chambers, as and for the purpose more fully set forth in said prior Letters Patent. These pipes *a'*, *b'* and *c'* will be supplied with air from some suitable blower. (Not shown.)

My improved traveling grate comprises a series of longitudinal grate-sections, embodying grate-bars and floor-plates, as hereinafter fully described. These sections are suitably supported, and are adapted to have, all together (or the major portion of them) a relatively slow forward movement, and to have, successively, a "quick-return" or relatively rapid backward movement. The series of bars are advanced, toward the left-hand in Fig. 1, by means of suitable actuating-devices, as will be hereinafter fully described; and during said advancing movement of the majority of the series, the bars are, a portion of them at a time, retracted to their original position. In other words, a quick-return movement is imparted to one or more (herein shown as two) of said bars, while the remaining bars of the series have a relatively slow advancing movement, or a movement in opposition to the direction of the return movement. During this quick-return movement of one or more of said bars while the majority of bars have a movement in the opposite direction, the fuel, resting in a mass, spread in a layer, upon the entire series of bars, has a greater resistance upon the several adjacent forwardly-moving bars than it has adhesion upon the one or more backwardly-moving bars. Therefore the layer or mass of fuel remains unbroken, and comparatively unaffected by the retractive movement of the relatively few bars. By means of this construction and organization of the mechanism, the layer, *L*, of fuel resting on the bars is carried uninterruptedly forward toward the rear end of the furnace, with a uniform movement coinciding with the forward movement of the majority of said grate-sections or bars, thus securing practically the same results as are obtained in furnaces employing an endless traveling grate, such, for instance, as shown in the patent hereinbefore referred to.

In practice, the proper operation of the mechanism will be facilitated by setting the grate somewhat at an inclination to a horizontal line, with its discharging-end lower than its receiving-end, as shown in Fig. 1 of the drawings, so as to secure the co-operation of gravity with the forwardly-moving bars to prevent retraction of the fuel by the retracting bars.

In the preferred form thereof herein shown, the grate consists of a series of substantially duplicate longitudinal sections, *D*, *D'*, *E*, *E'*, *F*, *F'*, arranged side by side, preferably in the same plane; and each section consists of a longitudinal grate-bar, or floor-plate supporting beam, *12*, and a series of floor-plates, *13*, removably secured to the upper side of said grate-bar or beam, as hereinafter described. These grate-bars will, preferably, be in the nature of channel-beams, each having side-flanges, *15*, *16*, connected at their upper edges by a web, or plate, having a series of perforations, or floor-plate-receiving sockets, formed therein, and also having remotely-disposed transverse flanges, *18* and *19*, at one end thereof, for a purpose hereinafter described; this construction being most clearly shown in Figs. 1 and 3 of the drawings.

The floor-plates *13* will preferably have their upper fuel-supporting faces slightly inclined longitudinally, as shown in Fig. 1, and will be constructed so that one end of one plate will partially overlap the other end of the next adjacent floor-plate of the series, as shown in said figure. Each floor-plate will be provided with a stem, *13'*, preferably integral therewith and adapted to fit the opening or socket, *20*, formed in the web *17* of the grate-bar *12*. These floor-plates will preferably be of width slightly greater than the width of the grate-bars, and each will, as shown in Fig. 2, be provided with a projection, *13''*, at one side thereof, to bear against the side face of the floor-plate of the next adjacent section; this construction forming air-spaces, *21*, intermediate to the plates of adjacent sections, through which air may be supplied to the fuel upon said floor-plates.

The construction of grate-bars and floor-plates herein described may be somewhat varied without departing from my invention.

As a means for imparting a slow forward movement to the successive grate-sections, and also for imparting a quick-return movement to a portion of the grate-sections as the balance thereof are moved forward, and to inaugurate said quick-return movement by imparting a sudden blow to the grate-bar *I* I have provided a cam-and-lever mechanism, which, in the preferred form thereof herein shown, consists, essentially, of a series of levers or slack-connected grate-bar-actuators, *22*, *22'*, *23*, *23'*, *24*, *24'*, fulcrumed at *25* upon and carried by rock-shafts, *26*, *27* and *28*, respectively (the ones *22* and *22'* being carried by the shaft *26*; the ones *23* and *23'* being carried by the shaft *27*, and the ones *24* and *24'* being carried by the shaft *28*, as clearly shown in Figs. 1 and 2), the cams *29*, *30* and *31* carried by the shaft *32* and adapted for actuating the series of levers, and means, substantially as hereinafter described, for actuating said shaft to rotate the cams. The cam-shaft *32* is herein shown supported in suitable bearings in the side walls of the furnace structure at the forward end thereof

and below the end of the grate-sections; and the three rock-shafts 26, 27 and 28 are located side by side intermediate to the cam-shaft and grate-sections, and are, also, supported in suitable bearings in the side walls of the furnace-structure. This cam-shaft is herein shown as provided with three duplicate cams, 29, 30 and 31, preferably of the spiral type, each of which has a quick-drop or let-off portion, 33. These cams are, preferably, secured to the shaft in different positions relatively to each other, as shown most clearly in Fig. 1.

The levers 22, 23 and 24, which actuate the rock-shafts 26, 27 and 28, respectively, have 15 downwardly-projecting arms, 22'', 23'' and 24'', which are preferably furnished with bearing-rollers, 22''', 23''' and 24''', at their ends, which rollers bear against the cam-faces of the cams 29, 30 and 31, respectively. The 20 upwardly-projecting arms of these levers movably engage the grate-bars of the grate-sections E', F' and D', respectively, as shown most clearly in Fig. 3, said upwardly-projecting arms extending between the transverse 25 flanges 18 and 19 at the ends of said grate-bars, as will be understood by reference to Fig. 1.

Secured to the shaft 26 which is actuated by the lever 22, is a rocking arm or short lever, 22', which engages the grate-bar of the 30 grate-section D. Secured to the shaft 27 that is actuated by the lever 23 is the rocking arm or short lever 23', which is connected with the 35 grate-bar of the section E'; and secured to the shaft 28 that is actuated by the lever 24 is the arm or lever 24', which is connected to the grate-bar of the section F'; all of said levers being connected to their respective grate-bars in a like manner.

40 It will be noticed, by reference to Figs. 4, 5 and 6 of the drawings, that the upper end of each actuating-lever is so connected with the grate-bar which it actuates as to have a limited amount of free movement, or play, 45 longitudinally thereof, at s, between the transverse flanges 18 and 19. The object of this construction or slack-connection is to enable the lever, on its retractive movement, to impart a sudden blow to the grate-bar to 50 start the same when the lower end of said lever passes the let-off point of the actuating-cam. By means of this device, whereby the 55 grate-bar is struck a blow when it is started back, any tendency of the grate-bar to stick or bind will be overcome, and the quick retraction thereof will, therefore, be facilitated.

As a means for retaining the levers or slack-connected grate-bar-actuators 22, 23 and 24 in close contact with their respective 60 actuating-cams, each of the shafts 26, 27 and 28 is provided at its ends with a weighted arm, 35. By this organization and arrangement of cams and grate-bar-actuating levers, it will be seen that each cam and the lever 65 contiguous thereto operate two grate-sections of the series, and that only two of said sections have a return movement simultane-

ously, the grate-sections adjacent to the sections being retracted moving in an opposite direction thereto.

As a means for actuating the cam-shaft 32, said shaft is provided at its outer end with a worm-wheel, 40, which meshes with and is driven by a worm, 41, upon a shaft, 42, journaled in bearings upon the outside of the side 75 wall 4 of the furnace-structure, said shaft 42 being provided with a suitable driving-pulley, 44, at one end thereof, as shown most clearly in Fig. 2 of the drawings.

Having thus described my invention, I 80 claim—

1. The herein-described grate-mechanism for furnaces, it comprising a series of longitudinally reciprocatory grate-sections, levers carried by rock-shafts and connected with 85 said sections, and means for actuating said rock-shafts to impart a relatively slow forward and a quick return movement to said sections successively, substantially as described.

2. The herein described grate-mechanism, 90 it comprising a series of longitudinally-disposed reciprocatory grate-sections, and means in connection with, and adapted for imparting a relatively slow advancing and a relatively rapid retractive movement to said sections, and consisting of a series of cams and a series of slack-connected actuators connecting said cams and grate-sections, substantially as described.

3. The herein-described grate-mechanism, 100 it comprising a series of longitudinally-disposed independently operable grate-sections and means consisting of a series of cams connected with said grate-sections by slack-connected actuators in position and adapted for 105 imparting a relatively slow advancing movement to some of said sections and a relatively rapid retractive movement to others of said sections, simultaneously, substantially as described.

4. The herein-described grate-mechanism for furnaces, it comprising a series of longitudinally reciprocatory grate-bars each of which has a series of removable floor-plates, 115 a series of rock-shafts adjacent to one end of said grate-bars, levers carried by said rock-shafts in engagement with the grate-bars, spiral cams having quick-drop or let-off portions, levers in operative connection with said cams and rock-shafts, weighted levers 120 connected with said rock-shafts to retain the levers in contact with their respective cams, and means for rotating said cams, whereby the grate-bars are reciprocated, substantially as described and for the purpose set forth.

5. In a furnace, the combination with a series of longitudinally reciprocatory grate-sections arranged side by side in parallelism to form a furnace-floor, and with a series of cams and their actuating mechanism, of a plurality of rock-shafts intermediate to said cams and grate-sections, a plurality of levers fixed to each rock-shaft and operatively connected with the ends of remotely-disposed grate-sec-

tions, a series of levers fixed one to each rock-shaft and bearing at its opposite end against its operating cam, and means for retaining all of said levers in operative engagement with said cams, substantially as described.

6. The herein described grate-mechanism for furnaces, it comprising a series of longitudinally reciprocatory bars, a series of levers carried by rock-shafts and connected to said bars so as to have a limited amount of free movement longitudinally thereof, and means in position and adapted for operating said rock-shafts to impart a relatively slow advancing movement and relatively rapid retractive movement to the bars, independently or successively, substantially as described and for the purpose set forth.

7. The herein described grate-mechanism for furnaces, it comprising a series of grate-sections, a series of levers carried by rock-shafts and connected with said grate-sections to have a limited amount of longitudinal movement independently thereof, a series of cams in connection with said levers and having let-off portions substantially as described, means for retaining the levers in operative connection with the cams, and means for rotating said cams to simultaneously advance certain of said sections with a relatively slow movement and retract others of said sections with a relatively rapid movement, substantially as set forth.

8. In a grate mechanism of the class specified, in combination a grate-bar supported for reciprocatory movement, a cam having a quick-drop or let-off portion, means for operating said cam, and a slack-connected grate-bar-actuator operatively connected with the grate-bar and cam and adapted, in connection with one portion of the cam to impart a

relatively slow advancing movement to the grate-bar, and in connection with the let-off portion of the cam to impart a sudden blow to the grate-bar to inaugurate the quick-return movement of said grate-bar, substantially as described.

9. In a grate-mechanism of the class specified, in combination a series of longitudinally reciprocating grate-bars adapted to have a relatively slow advancing movement and a quick-return movement, a series of slack-connected grate-bar-actuators, a series of cams adapted for imparting, through the medium of the grate-bar-actuators, a relatively slow advancing movement to said grate-bars, and having quick-drop or let-off portions in position and adapted for imparting a sudden movement to the grate-bar-actuators, separately or successively, whereby a sudden blow is imparted to the grate-bars to inaugurate the quick return movement thereof, and means for operating said cams, substantially as described.

10. In a grate-mechanism of the class specified, a grate-bar supported for reciprocatory movement, a grate-bar-actuating lever fulcrumed upon a rock-shaft and having a slack-connection at its upper end with the grate-bar, a cam having a quick-drop or let-off portion in position and adapted for imparting a sudden reciprocatory movement to the grate-bar-actuating lever to cause the same to impart a sudden retracting-blow to the grate-bar and means for operating said cam, substantially as described and for the purpose set forth.
